UNITED STATES PATENT OFFICE.

GUSTAV KOMAREK, OF CHICAGO, ILLINOIS, ASSIGNOR TO ST. LOUIS BRIQUETTE MACHINE COMPANY, OF ST. LOUIS, MISSOURI, A CORPORATION OF MISSOURI.

CHAIN FOR BRIQUET-MACHINES.

1,368,942.

Specification of Letters Patent. Patented Feb. 15, 1921.

Original application filed February 5, 1918, Serial No. 215,445. Divided and this application filed April 1, 1919. Serial No. 286,787.

To all whom it may concern:

Be it known that I, GUSTAV KOMAREK, a citizen of the United States, residing at Chicago, Illinois, have invented a certain new and useful Improvement in Chains for Briquet-Machines, of which the following is a full, clear, and exact description, such as will enable others skilled in the art to which it appertains to make and use the same, reference being had to the accompanying drawings, forming part of this specification.

My invention relates generally to briquet forming machines, and more particularly to a chain which is utilized upon one of the forming rolls of a briquet press between the mold rings thereof, and said chain constituting an end wall for the mold cavities in the rings.

This application is a division of the application filed by me February 5, 1918, Serial Number 215,445 and which resulted in Patent No. 1,295,764, dated February 25, 1919.

It will be understood that fuel briquets when formed are subjected to a relatively high degree of pressure and which action is necessary in order to produce briquets which will not break while being handled in transportation or delivery to the point of use and it is the principal object of my invention to provide a simple form of chain composed of solid flat links or links having flat outer faces, said chain being particularly applicable for use upon one of the pressure rolls or drums of the briquet machine disclosed in the patent aforesaid, and said chain being constructed so as to withstand the relatively high lateral pressures to which the briquets are subjected and said chain being constructed so as to minimize the wear upon its parts and particularly the overlapping parts which have bearing upon each other.

With the foregoing and other objects in view, my invention consists in certain novel features of construction and arrangement of parts hereinafter more fully described and claimed, and illustrated in the accompanying drawings, in which—

Figure 1 is a vertical section of parts of the pressure rolls or drums of a briquet machine and showing a chain of my improved construction positioned on one of said drums.

Fig. 2 is an enlarged horizontal section taken approximately on the line 2—2 of Fig. 1.

Fig. 3 is an elevational view looking against the inner face of one of the links of which my improved chain is constructed.

Fig. 4 is a horizontal section taken longitudinally through the centers of a pair of connected links.

Referring by numerals to the accompanying drawings, 10, 10 designate the coöperating pressure rolls or drums of a briquet machine, and carried by the peripheries of 65 said drums are mold rings 11 in which are formed mold cavities 12. Formed between these cavities are circumferentially disposed grooves 13 and arranged upon one of the drums and positioned in the grooves 13 70 therein are the chains of my improved construction.

Each chain is made up of a series of flat metal links 14 having smooth flat outer faces 15 and rounded ends 16. The inner faces 75 of the end portions of each link are recessed or cut away as designated by 17 in order to accommodate the corresponding end portions of the next adjacent links. This construction provides a centrally arranged 80 transversely disposed rib 18 on the inner face of each link, the end portions of said rib being widened as designated by 19.

Formed through the end portions of each plate 14 and in the centers of the cut-away 85 portions 17 are rivet holes 20 and formed in the inner face of each link within the cut-away portions and concentric with said rivet holes are annular grooves or recesses 21. Thus, when the links are fitted together or with the end portions thereof overlapping each other, the grooves 21 in the overlying end portions of a pair of the links constitute a circular chamber which is occupied by a bearing ring 22 of suitable wear-resisting 90 material, such as bronze. This bearing ring is preferably forced into the groove of one link before the latter is associated with the next adjacent link and thus said ring is anchored in one link and the next adjacent link 100 bears upon the projecting portion of said ring rather than upon the adjacent flat face of the link in which the ring is embedded.

As a result of such construction, a rela-

tively large wear resisting bearing is provided between the links and said bearing is effective in relieving the rivet between the links from all shearing strains.

- 5 The rivet holes in one set of links have their outer ends enlarged as designated by 23 in order to receive the heads of the rivets, and the outer ends of the holes in the opposite set of links are chamfered as designated 10 by 24 in order to receive the upset ends of the connecting rivets. The rivets which connect the links are of the type illustrated in Fig. 4, and the main body portion of each rivet is provided with an annular shoulder 15 25 which coincides with the joint between the inner faces of the overlapping portions of a pair of the links, such construction being effective in preventing the links from being rigidly connected when the ends of the 20 rivets are upset and forced into the chamfered portions 24. Each rivet is provided with an enlarged head 26 which occupies the enlarged portion 23 of the rivet hole. After the rivets have been properly set, it is 25 essential that their outer ends be machined or smoothed down so that they lie flush with the smooth flat outer faces 15 of the links.

Inasmuch as the chains are intended for use upon a drum or pressure roll, it is desirable, though not essential, that the edges of the links forming said chain be curved lengthwise, and said curved edges being formed on arcs of circles concentric with the axis of the drum on which the chains 30 35 operate. As a result, the inner portions of the chains completely fill and fit snugly within the grooves of the drum upon which they are positioned.

It will be understood that as the pressure 40 rolls or drums rotate to bring the mold cavities into coincidence with each other to form the briquets, the chains arranged between the coinciding mold cavities form the end walls for such cavities, and consequently said 45 chains receive all lateral pressure or pressure lengthwise through the bodies of the briquets at the time the latter are subjected to highest pressure. Inasmuch as the chains are disposed between the rows of mold cavities, the pressure upon the material between 50 the rolls is equal in both directions, or against the side faces of the chains. Consequently, the stresses due to high compression 55 are neutralized throughout the series of chains, and as a result, briquets of uniform density are produced.

Chains of my improved construction can be easily and cheaply produced, and are

very effective in performing their intended functions.

It will be readily understood that minor changes in the size, form and construction of the various parts of my improved chain can be made and substituted for those herein shown and described, without departing 65 from the spirit of my invention, the scope of which is set forth in the appended claims.

I claim:

1. The herein described chain composed of flat links, each of which has its end portions cut away on one side to receive the end portions of the next adjacent links, pivotal connections between the ends of the links, and bearing rings arranged between said links, which bearing rings are concentric 75 with said pivotal connections.

2. The herein described chain composed of flat links having rounded ends, and the end portions of one face of each link being cut away to receive the corresponding end portion of the next adjacent link.

3. The herein described chain composed of flat links having rounded ends, the end portions of one face of each link being cut away to receive the corresponding end portion of the next adjacent link, the end portions of said links being pivotally connected, and bearing rings between the end portions of said links, which bearing rings are concentric with the pivotal points between the 90 links.

4. In a chain of the class described, a link comprising a plate having a smooth flat face on one side, the end portions of the opposite face of said plate being cut away 95 to form recesses adapted to receive the end portions of the next adjacent links, and there being annular grooves formed in the faces of the recessed or cut-away portions of said plate.

5. In a chain of the class described, a link comprising a plate having a smooth flat face on one side, the end portions of the opposite face of said plate being cut away to form recesses adapted to receive the end portions of the next adjacent links, there being annular grooves formed in the faces of the recessed or cut-away portions of said plate, and there being apertures formed through 105 the end portions of said links, which apertures are centrally arranged within the annular grooves.

In testimony whereof I hereunto affix my signature this 28th day of March, 1919.

GUSTAV KOMAREK.
